UNITED STATES PATENT OFFICE.

DAVID D. BUICK, OF DETROIT, MICHIGAN.

CARBURETOR.

Application filed June 8, 1918. Serial No. 238,987.

To all whom it may concern:

Be it known that I, DAVID D. BUICK, a citizen of the United States of America, residing at Detroit, in the county of Wayne 5 and State of Michigan, have invented certain new and useful Improvements in Carburetors, of which the following is a specification, reference being had therein to the accompanying drawings.

10 This is an improvement in connection with a carburetor disclosed by my Patent No. 1,162,680, granted November 30, 1915, and besides having the same objects in view disclosed by this patent, my present invention aims to provide a more efficient carburetor that may be characterized in the following particulars.

First, there is a novel damper actuated and controlled metering pin, which, after 20 the main throttle of the carburetor is closed, permits of sufficient quantity of volatile liquid and fluid commingling to supply an engine with sufficient fuel for idling purposes.

25 Second, the metering pin of the carburetor is designed and constructed to provide a venturi and an auxiliary needle valve, so that volatile liquids may be drawn through the metering pin to commingle with fluid, 30 such as air, and supply an engine with fuel for various means; the supply of volatile liquid to the metering pin being regulated by the needle valve. The metering pin is constantly in communication with a supply 35 of fuel and has an apertured head through which air may be drawn to transfer fuel from said pin to the engine.

Third, the carburetor is characterized by 40 a novel air intake damper that may be controlled by a choke throttle when necessary to use one, and besides this air intake damper, there is an auxiliary air intake valve disposed and constructed so as to permit of easy access being had to the metering 45 pin for adjusting the needle valve thereof.

Fourth, there are practically three supplies of air for the carburetor, one being constant so that the engine may idle, another being optional so that a lean or rich mixture 50 may be had according to the quality of fuel, and the remaining source of supply being drawn on as the speed of the engine increases.

The above are a few of the principal features of the carburetor and others will ap-

pear, together with the advantages derived therefrom as the nature of the present invention is better understood.

Reference will now be had to the drawings, wherein—

Figure 1 is a vertical sectional view of the carburetor;

Fig. 2 is a similar view taken at right angles to the section shown in Fig. 1;

Fig. 3 is a plan of a portion of the carburetor;

Fig. 4 is an enlarged sectional view of a portion of the carburetor, taken on the line IV—IV of Fig. 1, and

Fig. 5 shows detail views of a damper 70 adapted to form part of the carburetor.

In describing my invention by aid of the views above referred to, I desire to point out that the same are merely illustrative of the carburetor as now constructed, and I do not 75 care to confine my invention to the precise construction and arrangement of parts shown, other than defined by the appended claims.

In the drawing, the reference numeral 1, 80 denotes a carburetor casing providing a carbureting chamber 2, and the bottom of said casing has a central depending tubular stem 3 with the lower end thereof enlarged and flanged, as at 4, and screwthreaded as at 5, 85 so that a float chamber 6 may be mounted upon the lower end of the stem 3 and be retained thereon by a nut 7 or other fastening means.

The float chamber 6 engages a closure 90 plate 8, carried by the casing 1 and this closure plate has one side thereof provided with an enlargement 9. In the enlargement 9 is an air vent 10 for the float chamber and intake ports 11 and 12, the former being controlled by a conventional form of needle valve 13 slidable in the enlargement 9 and actuated by a float 14 within the chamber 6 and pivotally connected to the enlargement 9, as at 15. The port 12 is adapted to 100 be connected to a suitable supply of volatile liquids, as gasoline.

The lower end of the stem 3 is closed by a detachable plug 16 and the bore 17 of said stem communicates with the chamber 6 105 through a port 18. The lower end of the bore 17, below the port 18, constitutes a water well in which water carried in by the fuel may accumulate instead of in the float chamber 6, thus allowing the water to be 110

carried off in small quantities, without any danger of a large quantity causing a cessation in the operation of the engine. The stem 3 has a longitudinal port 19 establishing a constant communication between the bottom of the carbureting chamber 2 and the atmosphere, and in the bore 17 of said stem is a bushing 20 for a metering pin 21 that extends into the carbureting chamber 10 of the casing 1. The upper end of the metering pin 21 has a head 22 and one side of the head is provided with a lateral slot 23 and the opposite side of the head with an opening 24, said opening having converging walls and communicating with the slot so as to form a venturi, as best shown in Fig. 1. The top of the head 22 has an interiorly screwthreaded boss 25 for an auxiliary needle valve 26 extending into the slot 23 and movable to and from the upper end of a longitudinal port 27 in the metering pin 21. Besides this longitudinal port, the metering pin 21 has opposed longitudinal grooves 28 tapering towards the upper end of the pin, 25 with the lower ends of the grooves communicating with the port 27 through transverse ports 29. The small ports 29 cooperate with the large port 27 in establishing communication between the carbureting chamber 2 and the float chamber 6, and by raising and lowering the metering pin in the bushing 20 there will be a variable supply 30 of gasoline to the carbureting chamber. The tapering grooves 28 permit of a minimum or 35 maximum supply of gasoline to the carbureting chamber and the supply can be proportioned relative to the intake of air and also in proportion to the suction or reduction of atmospheric pressure in the carbureting chamber by raising and lowering the metering pin 21.

One side of the casing 1 has an angularly disposed air intake connection 30, preferably rectangular in cross section and projecting 45 from the end of this connection are apertured lugs 31. Pivotaly mounted between the lugs 31 by a pin 32 is a barrel 33 having web portions 34 and said web portions are connected by a damper 35 adapted to practically close the connection 30. The outer end of the damper 35 has a lip 36 adapted to engage the end of the connection 30 and limit the closing movement of the damper, and the inner end of the damper is bifurcated, as at 37, to embrace the head 22 of the metering pin 21, and provide side stops 38 to press upon the bottom of the chamber 2 and limit the closing movement of the damper. In the bifurcation 37 of the 55 damper are bearings 39 extending into the slot 23 of the pin head 22, at the sides of said head. The bifurcated end of the damper is furthermore cut away, as best shown in Fig. 5, so as not to obstruct passage of air to the central portion of the slot

across the upper end of the port 27 and out of the opening 24.

In some climates, for instance, where the air is rarefied and unbalances the usual constituent parts of a good mixture, it may be 70 necessary to provide the air intake connection 30 with a choke throttle 39 arranged in an elbow 40 suitably connected to the connection 30. The choke throttle 39 will be limited in its opening movement by a protuberance 41 in the elbow 40 and said throttle will have an angularly disposed portion 42 to press against a crank 43, carried by the barrel 33 of the damper 35, so that when the choke throttle is closed, the damper will be 75 automatically raised and impart a similar raising movement to the metering pin, gradually increasing the area of the orifice at the upper end of the bushing 20 formed by the tapering recess 28. Since the crank 80 43 is not connected to the throttle portion 42, the damper may be raised independent 85 of any movement of the throttle 39.

That side of the carbureting casing 1, opposite the air intake connection 30, has a 90 manifold connection 44 provided with the usual and well known type of throttle 45. The shaft 46 of the throttle has the outer end thereof provided with a lever 47 and said lever has crank portions 48 and 49, 95 the latter provided with a set screw 50. The crank portions 48 and 49 are adapted to press against a lug 51 carried by a tubular valve body 52 above the carbureting chamber 2. The valve body 52 is ported, as at 100 53, and rotatable therein and on the valve body, is a ported cap 54 adapted to establish communication between the valve body 52 and the atmosphere.

The cap 54 is provided with a handle 55 105 so that said cap may be rotated upon the valve body and retaining said cap on the valve body is a yoke 56 having a central depression 57 engaging in a recess 58 centrally of the top of the cap. The periphery of the cap is cut away to provide shoulders 59 and these shoulders are adapted to engage the lug 51 and limit the rotative movement of said cap and thus define the open and closed 110 positions of said cap relative to the valve body 52.

Considering the operation of the carburetor, I will assume that the main throttle 45 is almost closed, with engine idling. Under such circumstances, the damper 35 is closed 115 except for a small passage beneath the throttle and the air admitted to the carbureting chamber 2 is either received through the port 19 of the stem 3, through the valve body 52, or a small quantity passing under the 120 damper 35, but principally from the port 19. In either instance, the suction or reduction of atmospheric pressure within the carbureting chamber is such as to maintain a column 125 of gasoline in the port 27 and a draft of air 130

through the slot 23 and the opening 24 of the head 32, causes a sufficient quantity of gasoline to be withdrawn from the port 27 to sustain combustion within the cylinders of an engine for idling purposes.

When increasing the speed of the engine by opening the main throttle 45 and advancing the spark the suction on the upper face of the damper 35 within the carbureting chamber 2, is sufficient to raise the damper 35 and consequently the metering pin articulated therewith. This operation is facilitated by an inrush of air at the port 19 and by air passing under the damper and through the connection 30. As the metering pin is elevated the grooves 28 thereof are brought into communication with the carbureting chamber and consequently there is an additional and gradually increasing supply of gasoline to said chamber, the supply increasing as the metering pin is elevated and maximum speed is reached. It is through the medium of the adjustable cap 54 that a lean or rich admixture of gasoline and air may be obtained, and when the choke throttle 39 is employed it is possible to reduce the supply of air to the carbureting chamber and maintain a full supply of gasoline thereto, thus obtaining an exceedingly rich mixture.

What I claim is:

1. A carburetor casing having a carbureting chamber therein and adapted to communicate with the atmosphere, a float chamber constantly in communication with the carbureting chamber and adapted to provide a constant supply of volatile fluid for engine idling purposes, a metering pin establishing communication between the float chamber and the carbureting chamber and having a groove in the wall thereof establishing an additional communication between said float chamber and said carburetor chamber for variable speeds of an engine, and means carried by said metering pin causing air to travel transversely of the direction of the flow of fuel to lift the fuel from said metering pin.

2. In a carburetor, a carbureting chamber having an air intake connection and a lateral fuel outlet connection, a float chamber adapted to supply volatile liquid to said carbureting chamber, a metering pin constantly in communication with said float chamber so as to receive fuel therefrom, a head carried by said metering pin within said carbureting chamber and providing a venturi transversely of said metering pin, and in the plane of the lateral fuel outlet connection and means articulated with said metering pin and controlling the supply of air through said air intake connection.

3. In a carburetor, a carbureting chamber, a float chamber adapted to supply a volatile liquid thereto, an adjustable metering pin in

said carbureting chamber having a port constantly in communication with said float chamber, a head carried by said metering pin provided with a transverse venturi adapted to remove sufficient volatile liquid from the port of said metering pin to maintain idling of an engine, and automatically actuated means engaging said head adapted to raise said pin.

4. In a carburetor, the combination of a carbureting chamber having an air intake connection and a fuel outlet connection, a float chamber, a metering pin constantly in communication with the float chamber and said carbureting chamber and having a Venturi passage transversely in the upper end thereof, a needle valve extending into the Venturi passage of said pin, and a damper for the air intake connection of said carbureting chamber, said damper having bearings in the upper end of said metering pin so that said pin and damper may be simultaneously adjusted.

5. In a carburetor, the combination of a carbureting chamber having an air intake connection and a fuel outlet connection, a float chamber, a hollow metering pin constantly in communication with said float chamber and said carbureting chamber and having a Venturi passage transversely of the upper end thereof, a needle valve extending into the Venturi passage of said pin, a damper at the outer end of the air intake connection of said carbureting chamber and connected to said metering pin so as to move in synchronism therewith, and a choke throttle adapted to press against said damper and cause said damper to shift said metering pin.

6. A carburetor comprising a casing, a float chamber below said casing, a tubular stem in said float chamber communicating therewith and having an air port open to the atmosphere and into said casing, said stem having a water well in the lower end thereof below and in communication with said float chamber, a metering pin in said stem establishing communication between said stem and said casing, and a damper in said casing connected to said pin and positioned above the air port of said pin so that an increased velocity of air through said port tends to open said damper and raise said metering pin.

7. A carburetor comprising a casing having a side fuel outlet and an air port constantly in communication with the atmosphere a metering pin constantly in communication with a supply of fuel and extending into said casing, a head on said metering pin having a transverse opening supplied with fuel from said pin and with air from said air port so that air will pass through said head in a direction at approximately a right angle to the fuel emitted by

the metering pin and cause the fuel and air to commingle, and a valve above said metering pin adapted to supply air to said casing.

8. A carburetor comprising a casing having a side fuel outlet and an air port constantly in communication with the atmosphere, a metering pin constantly in communication with a supply of fuel and extending into said casing, a head on said metering pin having a transverse opening supplied with fuel from said pin and with air from said air port so that fuel and air may be drawn from said head, a needle valve carried by said head adapted to restrict only the transverse opening therethrough, means adapted for adjusting said metering pin, and a detachable valve above said metering pin adapted to supply air to said casing and permit of said needle valve being adjusted.

9. A carburetor casing having a carbureting chamber therein and adapted to communicate with the atmosphere, a float chamber constantly in communication with the carbureting chamber and adapted to provide a constant supply of fuel content of the charge for engine idling purposes, a metering pin establishing communication between the float chamber and the carbureting chamber and having means in the wall thereof establishing an additional communication between said float chamber and said carburetor chamber for variable speeds of an engine, and means carried by said metering pin causing air to travel transversely of the direction of flow of fuel to lift fuel from said metering pin.

10. A carburetor casing having a carbureting chamber therein and adapted to communicate with the atmosphere, a float chamber adapted to supply the fuel content of the charge for the engine, a metering pin operative in the delivery of such fuel supply to the carbureting chamber and formed to provide for and permit constant communication between the chambers and to provide additional communication therebetween by movements of the pin, said additional communication being inactive during periods of engine idling and made active

during variable speed conditions of the engine, and means carried by the metering pin for causing air to travel transversely of the direction of flow of fuel to lift fuel from said metering pin.

11. A carburetor casing having a carbureting chamber therein and adapted to communicate with the atmosphere, a float chamber adapted to supply the fuel content of the charge for the engine, a metering pin operative in the delivery of such fuel content to the carbureting chamber and formed to provide for and permit constant communication between the chambers and to provide for additional communication therebetween in presence of pin movements, said additional communication being inactive during periods of engine idling and made active during variable speed conditions of the engine, and means carried by the metering pin and permanently positioned with respect to the channel of constant communication of the pin and operative to cause air flow transversely of the direction of fuel flow to the outlet of such communication channel.

12. A carburetor casing having a carbureting chamber therein and adapted to communicate with the atmosphere, a float chamber adapted to supply the fuel content of the charge for the engine, a metering pin operative in the delivery of such fuel content to the carbureting chamber and formed to provide a channel of constant communication between the chambers and to provide additional communication therebetween in presence of pin movements, said additional communication leading from said channel and being inactive during periods of engine idling and made active during variable speed conditions of the engine, and means carried by and permanently positioned with respect to the channel of constant communication of the pin and operative to cause air flow transversely of the direction of fuel flow to the chamber outlet to such channel.

In testimony whereof I affix my signature.

DAVID D. BUICK.
